DEPTH-REGULATOR FOR SUBMARINE
MINES IN TIDAL WATERS

Demeter Rudmann, Fiume, Italy

Application January 19, 1935, Serial No. 2,509
In Italy October 13, 1934

1 Claim. (Cl. 102—3)

My invention relates to a depth regulator for submarine mines particularly intended for use in tidal waters and where there are currents of variable strength. It is a known fact that in such waters the mines are commonly either too low or too high, according to the variations in the depth of the water and the strength of current. The object of my new depth-regulator is to keep mines at a correct constant depth below the level of the water.

In the present apparatus embodying my invention the raising and lowering of the mine are effected by a mooring rope wound upon a drum which is indirectly energized by the current and controlled by the external hydrostatic pressure. The new depth-regulator is distinguished from all others essentially by the fact that it is an entirely separate supplementary mechanism which is applicable to every kind of submarine mine without the necessity of either the shell or the anchor-gear of the mines being modified.

Moreover the new depth-regulator is provided with safety-gears and accessories capable of insuring perfect working, and all difficulties liable to arise from incrustation of shells, seaweed and the like, are avoided because all delicate mechanisms (such as wheel-gears, engaging clutch, pressure diaphragms etc.) are enclosed in a casing filled with lubricating substance.

The depth-regulator embodying my invention is illustrated in the accompanying drawing, in which

Fig. I shows its application to a mine of spherical shape.

Figs. II and III show two moored mines provided with depth-regulator, the first immediately after the laying, the second in definitive position.

Fig. IV shows a central section through the depth-regulator in which are visible essentially three parts.

(1) *The head.*—The head 21 comprises an inner casing 14, including the engaging clutch 41—52 and 41—18 respectively for forward and reverse transmission; two reducing worm-wheel-gearings 49—50 and 48—46; the principal toothed wheel 45 which meshes with the fixed gearing 44 of the outer casing; the inverting gearings 54—17—53—51 for rearward transmission; and finally the stop-gear 55—15, 16—17.

(2) *The rope-drum.*—This rope-drum 22 is attached to the inner casing 14 of the head. Beneath the rope-drum there are provided three rope leading rollers 40—41—42 (the last roller is movable also in axial direction in order to insure

a regular winding-up of the rope); and the safety-gear against mooring shock 38—37—36—35—43.

(3) *The turbine.*—The turbine is equipped with outwardly projecting blades 33. The turbine turns upon a central pivot attached to the rope-drum and includes two pressure-sensitive-diaphragms 24—26; the immersion-spring 28; and the friction-clutch 29 which connects diaphragm 26 with the engaging axle 34.

Figure I shows, how the depth-regulator is to be fastened to a spherical mine, which is the most commonly used.

At the place for attaching the usual mooring rope is shackled the upper end of a little chain 6 of about one meter in length, which chain then passes over a support-bolt 1 (which may be screwed eventually on the place of a lead-horn). The other end of the chain is fastened by means of a swivel 2 and a shock-absorber 3 to the head 21 of the regulator.

Thus the regulator rests with its head against a rubber (or cork) bolster 4 at the right side of the mine-shell. The chain 6 which keeps suspended the apparatus and the mooring rope 7 which holds it to the anchor must be well stretched in order to avoid damages to the mechanism by the latter bumping against the mine during mooring act.

After a short stay in water the loosening gear 8 of the mine lets the anchor go, the mine turns to the right side due to the absence of balance and the tension of rope. The chain 6 drops consequently from its support-bolt 1, and thus the situation shown in Figure II arises.

The depth-regulator is applicable to every kind of moored mines however they may be shaped (spherical, cylindrical, oval or otherwise) and however its mooring gear may be shaped (plummet gear, hydrostatic gear etc.).

Because of the necessity of resisting the lowering effect of strong currents, the actual mines with fixed mooring length are provided with a great deal of residual buoyancy. It is therefore sure that all sorts of submarine mines are able to bear the weight of the depth-regulator without any difficulty. The partial loss of buoyancy due to the weight of the regulator does not reduce the efficiency of the mines, as the regulator compensates entirely the lowering effect of current by a corresponding lengthening of the mooring rope.

Only in case the mine is provided with an automatic contact-breaker controlled by tension of the mooring rope (safety gear for mines with broken moorings), it will be necessary to replace the safety-gear-spring by a new one of greater

strength, strong enough to compensate the weight of the depth-regulator.

In the position shown in Figure II the tension of the mooring rope does not yet set the rope-drum at work, but only the safety-gear 38—36—35 shown in Figure IV, which has the task of supporting the first mooring shock arising at the moment of touching ground by plummet.

The mooring rope is fastened by two links 38—36 to the lower end of the regulator-rope 39 which remains however a little slack, as shown in Figure II, at 10. Thus the first shock of mooring is transmitted not to the internal mechanisms—but to the depth-regulator casing and to the 15 shock-absorber 9 inserted in the chain respectively (Figure II).

After being some time in the water when the rope-drum 22 has made about $\frac{1}{10}$ of a revolution, the nose 43 of the spring-bolt 35 is released. The 20 bolt moves to the left, and the link 36 drops. The mooring rope is now hanging directly on the regulator-rope 39 (position shown in Figure III). The second shock, due to the dropping of link 36, is obviously very slight, since the stretching by 25 a few centimeters of the slack 10 in rope 39, (Fig. II) permits only a slight acceleration of the mine.

As shown by Fig. III, the depth-regulator, when the mine is definitely anchored, hangs a distance 30 of about one meter beneath the mine and the blades 33 of its turbine are exposed to the effect of the current. In the drawing only two vanes are shown 33 but in reality there are 20—24 of such blades.

35 Due to the effect of the swivel at 11 and 13 and to the circumstance that the centre of the hydrodynamic pressure is situated behind the suspension-point 19 or 20, the depth-regulator always 40 swings away from the current and thus keeps its longitudinal axis exactly in the direction of the current.

Under the effect of the current the turbine 45 keeps up a slow continuous rotation (about 17 revolutions a minute in a current of two miles an hour) which is always in the same sense with regard to the mooring-rope. The power deployment of the mechanism depends on the dimension of the turbine, on the ratio of reduction of the gear wheels and obviously also on the speed 50 of current. Experiments have demonstrated—they may easily be checked by calculation—that acceptable dimensions of the turbine guarantees the necessary power for a reliable performance of the depth-regulator, even in currents of feeble 55 strength (one mile an hour). When however the current rises above a speed of two miles an hour, there will then arise an excess of power. The reduction ratio of the internal gear-wheel is to be kept obviously rather high, about 500:1.

60 The revolutions of the turbine, are communicated by diaphragm 26 and friction clutch 29 to the engaging axle 34. When the mine is deeper than predetermined by the tension of the immersion-spring 28, an external pressure of the water, 65 penetrating through the apertures 23, is exerted on the diaphragm 24 which pressure is communicated to the lubricating oil filling the space between the two diaphragms 24 and 26. Due to the incompressibility of the oil and to the fact 70 that the pressure exceeds the tension of the immersion-spring 28, the diaphragm 26 moves to the right in Fig. IV and moves along also the engaging axle 34 to the right.

This causes clutch members 47—18 to engage 75 and the reverse transmission 54—17—53—51—

49—50—48—46—45—44 to work. The whole inner casing 14 and rope-drum 22 rotate in an opposite direction to the turbine, and the rope 39 is being unwound with result that the mine rises. The movement is quite slow due to the high reduction ratio of the two worm-wheel-gearings working in series. The drum unrolls about three meters of rope during an hour in a current of two miles.

When the mine, due to the unrolling of the rope, has risen to a height in which there exists a balance between the external pressure and the force of the immersion-spring 28, the engaging axle 34 is moved back to the left and the clutch-members 47—18 become disengaged with the result that the mine ceases its rising movement, as it has arrived at the predetermined right depth. In this position the slow rotation of the turbine continues without moving the internal wheel-gearings. It should be mentioned that the rope 20 cannot unroll under the effect of its own tension under any circumstance; the worm-wheel-gearings act as an automatic stop.

If the mine—by the unrolling of the rope—should exceed the proper depth and rise too high, the tension of the spring 28 (due to the weakening of the external pressure) would displace the engaging axle yet more toward the left with the result that the clutch-members 47 and 52 become engaged. Thus, would come into action the forward transmission 52—49—50—48—46—45—44 and the gearings 51—53—17—54 would run without load. The inner casing 14 and the rope-drum 22 would rotate this time in the same sense as the turbine. The rope would therefore wind 35 upon the drum instead of unrolling therefrom, as it did in the first case, and the mine would descend.

As experiments have shown, the sensibility of the hydrostatic gear for depth-differences can be 40 increased to a ratio which responds also to 20 centimeters of level-difference, which is more than accurate enough for practical purposes. And it need not be feared that due to the continuous working, the pinions will be subjected to any 45 great wear and tear. The pinions have a force of about 3/1000 of the rope-tension exerted on them. Therefore, it is always possible to give them dimensions which secure a minimum specific pressure, eventually also by an increase in 50 the number of pinions up to 8 or 12.

In order to prevent excess rotation of the rope-drum beyond the limit of about ten meters of rope (that is practically the necessary length) the apparatus is provided with a stop-gear acting 55 on the wheel 17.

It should be noted that in Figure IV, for the sake of clearness, there is omitted a vertical axle which connects movement of worm 48 (by means of a worm-wheel) with the worm-gear 55. Due 60 to the very slow movement produced by three worm-wheel-gearings, working in series (49—50, 48—55, 55—15), the stop-nose 16 accomplishes only $\frac{1}{3}$ of a revolution during the entire unrolling of ten meters of rope. The wheel 16 twice stops 65 the movement of the nose 17, the first time when the rope is completely wound up, and the second time when the rope is completely wound off. Returning of nose 16 is obviously possible only in the case that after a stopping there sets in a 70 movement in the opposite sense to that stopped; the latter is absolutely prevented.

In order to prevent overworking of the sensitive diaphragms and of the internal wheel-gears, the depth-regulator is provided with a safety- 75

gear which comprises a friction-clutch 29 inserted between diaphragm 26 and axle 34. In all cases in which for the turning of axle 34 a stronger force would be required than that of the friction clutch-spring 29 (for example when 5 wheel-gears are stopped by the stop gear) the friction clutch permits the rotation of the turbine also without simultaneous rotation of the engaging axle 34.

In order to prevent deformation of the pressure sensitive diaphragms 24 and 26 due to overworking through exceptionally strong external pressures (for example in the case of irregular 10 mooring) there are provided two fixed walls 25 resp. 27, which limit the possible movements of 15 the diaphragms in a way which does not interfere with their elasticity.

The depth-regulator has an advantage which ought to be once more emphasized, to wit, all its 20 somewhat delicate mechanisms are completely enclosed in a casing filled with lubricating substance, thus being well protected against incrustations of shells and the like. Well dimensioned 25 stuffing boxes (omitted from the drawing for sake of clearness) avoid, or at least retard, loss of the lubricating oil. Also when after being a long time in water, instead of pure oil an emulsion arises, that has slight damaging influence on the 30 functioning of the regulator, as a good dose of arsenic or other poison added to the oil pre-

vents the growth of incrustations in the interior of the regulator.

And finally when perhaps, after having for 5 many years been in water, the depth-regulator will effectively cease to function, and the mines provided with the depth-regulator will thus become exactly like a mine without it (probably due to incrustations of the rope by shells not sufficiently eliminated by the diurnal winding 10 up and down) then there will still be the possibility to take the mines up, clean and to lay them again, at least in mine-fields of defensive nature.

I claim as my invention:

A depth regulator for a submarine mine having mooring means therefor, including a mooring cable, said depth regulator comprising a rotatable drum, a casing therefor, a rope coiled thereon and adapted to be connected to said mooring cable, a rotatable axle carrying said drum, means intermediate said axle and said drum for transmitting rotation to said drum in either direction, a turbine operatively connected to said axle, and a safety-gear intermediate said rope and said mooring cable, comprising a spring-controlled bolt movably mounted in said casing, a means 15 retaining said bolt in position, chain-links intermediate said mooring cable and said rope and held by said bolt in inactive position and adapted to operatively connect said mooring cable with 20 said rope upon the release of said bolt.

DEMETER RUDMANN.
